(57) **CLAIM**

We claim the ornamental design for a utensil bowl, as shown and described.

DESCRIPTION

FIG. 1 is a top perspective view of an exemplary embodiment of a utensil bowl illustrating our new design;

FIG. 2 is a top plan view thereof;

FIG. 3 is a right side elevational view thereof, the left side elevational view being a mirror image of the right side elevational view shown;

FIG. 4 is a bottom plan view thereof;

FIG. 5 is a front end elevational view thereof;

FIG. 6 is a rear end elevational view thereof; and,

FIG. 7 is an enlarged fragmentary front elevational view of the utensil bowl taken along line 7—7 of FIG. 5.

The ornamental design which is claimed is shown in solid lines in the drawings. The broken lines in the drawings are for illustrative purposes only and form no part of the claimed design.
